tion of Delaware

Application April 22, 1944, Serial No. 532,256

11 Claims. (Cl. 179—100.3)

1

This invention relates to motion picture sound apparatus and particularly to a rerecording system wherein a plurality of sound records are combined into a composite sound record.

In the production of sound motion pictures, it is well-known that the pictures are usually photographed on one film and the dialogue is usually recorded on a separate film. Also, on additional films, there may be recorded background noises or sound effects, such as hoof beats, crowd noises, etc., as well as music. The sound effect records may have been recorded prior to the particular picture being made and be in the form of loops which are reproduced simultaneously with the dialogue, music, and other records. During the rerecording process, the volume of the various separate tracks or records are varied in the proper proportion to make a single complete record which has the proper timing, balance, and dramatic effect.

For instance, in the recording of a dance scene or storm scene, it is desirable to have the background music and storm noises decrease in volume during a conversation or other dialogue, and this has been accomplished in the past by either having the mixer manually reduce the volume of the music during the dialogue sequences or by having the dialogue signal automatically reduce the music or effects level. A system of the latter type is disclosed and claimed in Mueller Patents Nos. 1,868,467 of November 22, 1932, and 2,075,861 of April 6, 1937. In such an automatic system, the timing and reduction of the volume is solely dependent upon the dialogue signal. Thus, if there were pauses between words or between sentences, the level of music or other background sounds would actually rise during such periods. It has been found desirable, however, to maintain the background signal at a predetermined low level during an entire dialogue sequence regardless of the length of the pauses therein. It has also been found preferable in order to obtain the proper relationship between the increases and decreases in the different signals, to have the background sounds begin to diminish prior to the beginning of the dialogue and to begin to fade back prior to the end of the dialogue sequences. With an automatic system controlled by the dialogue signal only, or with manual control, these results cannot be accomplished in the uniform manner desired.

The present invention, therefore, is directed to a system which is automatic to the extent that the level of the music or other sound effects is reduced in accordance with a special type of pre-

2

constructed control track prepared for a particular sound track or picture. Control track systems for varying the reproduced volume of a signal are well-known, one such type of system being disclosed in Burrill Patent No. 2,270,260, of January 20, 1942. This patented system employs a variable area control track on the film intermediate the sprocket perforations. A reproducing system employing a control track having a constant frequency and varying amplitude is disclosed in Weinberger Patent No. 1,850,701, of March 22, 1932, while a control track rerecording system using a constant frequency and variable amplitude tone is disclosed and claimed in Wolfe Patent No. 2,279,018, of April 7, 1942. The present invention, however, is directed to a control track having a constant amplitude and constant frequency.

From the above, it is apparent that various types of control tracks may be used for controlling the volume of a signal track and that the music or sound effects track may be automatically reduced in volume during the dialogue sequences while rerecording. However, in the present invention, a constant amplitude, constant frequency control track is synchronized and timed in a novel manner with the beginning and end of each dialogue sequence to automatically accomplish a new mixing operation of a plurality of tracks being rerecorded.

The principal object of the invention, therefore, is to facilitate the rerecording of a plurality of sound records into a single record.

Another object of the invention is to provide an improved rerecording system wherein one sound track is reduced in amplitude during time periods determined by a control track preconstructed in accordance with the occurrence of the sound sequences on another sound track.

40 A further object of the invention is to provide an improved method of rerecording a plurality of sound tracks into a single track whereby the level of one track is automatically controlled with respect to the occurrence of sound sequences on another track.

45 A further object of the invention is to provide an improved rerecording system wherein a pre-setting of the automatic reduction of volume of one record can also be manually controlled during the rerecording operation.

50 A further object of the invention is to predetermine the time of reduction and the amount of increase in volume of one record in any desired relationship with respect to the occurrence of the sound sequences on another record.

Although the novel features which are believed to be characteristic of this invention will be pointed out with particularity in the appended claims, the manner of its organization and the mode of its operation will be better understood by referring to the following description read in conjunction with the accompanying drawings forming a part hereof, in which:

Fig. 1 is a diagrammatic view of a rerecording system embodying the invention.

Fig. 2 is a diagrammatic view showing the manner of synchronizing a plurality of sound tracks with respect to a control track, and

Fig. 3 is a schematic circuit of the automatic volume control portion of the system shown in Fig. 1.

Referring now to Fig. 1, a plurality of reproducing sound heads or phonographs are shown at 5, 6, 7, and 8, reproducer 5 translating a constant frequency, constant amplitude tone such as 1000 cycles per second, although other frequencies or forms of control tracks may be used, into corresponding electrical currents, while reproducers 6 and 7 translate music and sound effects tracks into respective corresponding electrical currents. Reproducer 8 performs the same function for a dialogue track. Although the invention is described as embodied in a sound film rerecording system, it is to be understood that the rerecording may be from disc records to a disc record, from disc records to a film record, or from film records to a disc record. The invention may also be used in the straight reproduction of sound records. The outputs of the reproducers 5 to 8, inclusive, are shown connected by conductors 10, 11, 12, and 13 to potentiometers 15, 16, 17, and 18, respectively, mounted on a mixing console 20. These potentiometers are for the purpose of manually varying the volume of the electrical currents from the output of the reproducers in a well-known manner.

After modification by the potentiometer 15, the control tone is impressed upon a control tone rectifier 22 over conductor 23, the rectified current output being impressed over conductor 24 on a variable gain amplifier 26. In the control tone circuit, an amplifier may be used intermediate the potentiometer 15 and rectifier 22, or between the potentiometer 15 and soundhead 5. The outputs of potentiometers 16 and 17 are combined and then impressed over conductor 28 on the variable gain amplifier 26. The dialogue currents are transmitted over conductor 29 to one of the primaries of a transformer 31, while the output of the variable gain amplifier 26 is transmitted over conductor 32 to a second primary of the transformer 31. The secondary of transformer 31 is connected over conductor 34 to an amplifier 35 which feeds a recorder 37 over conductor 38. For clarity, the elements of Fig. 1 are shown connected by single conductors.

In the usual rerecording system, the mixer controls the level of the output of each reproducer in accordance with a cue sheet thereby controlling the fading in and out of the music and background effects. In the present invention, the reduction and increase in volume of the music and sound effects is under control of a control track, the mixer, however, having control of the amount of uniform variation introduced by the control track. The times at which the control track acts on the background effect currents with respect to the dialogue track currents is obtained by the placement of the control track with respect to the occurrence of the various signal track se-

quences, while the rate at which the control track acts upon the background effect currents is obtained by the timing of the electrical circuits of the control track as will now be explained.

Referring now to Fig. 2, a control track is shown at 40 having a start mark 41, constant frequency-constant amplitude tone sections 42, and opaque leader sections 43. A dialogue track is shown at 45 with its start mark 46, its dialogue sections 47, and its opaque leader sections 48. The music track is shown at 50 with its start mark 51, its opaque leader section 52, and its music section 53, while the sound effects track 54 has a start mark 55, an opaque section 56, and a sound effects section 57. The music and sound effects may be continuous over an entire scene, or also made up in sections with opaque leader sections in any suitable manner as is well-known in the art. Furthermore, many pictures require several background effect tracks while others may use only a single track in addition to the dialogue track.

From the arrangement of the tracks in Fig. 2, the start marks are all lined up at some predetermined point, such as the reproducing aperture 25 when the films are threaded in their respective reproducers 5, 6, 7, and 8. Since the films are then advanced simultaneously at the same acceleration and speed, the reproduction of each track will occur as shown in Fig. 2. As the films are reproduced, the music and sound effects come in first before the first dialogue sequence. However, ten frames before each dialogue sequence which, since the films are advanced at the rate of 24 frames per second, corresponds to slightly less than one-half second, the control track 40 begins reducing the gain of the variable gain amplifier 26 by an amount determined by the setting of potentiometer 15. The control track then ends 4 frames before the ending of each dialogue sequence which corresponds to $\frac{1}{6}$ second. This amount of anticipation has been found to provide a particularly smooth fade out and in of the music and/or sound effects which is practically unnoticeable by the listener while providing excellent intelligibility of the dialogue, since it insures understanding of the first word of each dialogue sequence. These results are enhanced by the electrical timing of the control circuit which will now be described in connection with Fig. 3.

In Fig. 3 the primary of a transformer 30 may be connected to either the potentiometer 15 or to a tone amplifier. The secondary of transformer 30 is connected to the anodes of a full wave rectifier 32, the output of which is impressed on a timing filter consisting of condenser 33 and resistor 34 in parallel. The timing filter is connected to the control grids of the variable gain amplifier 26 for varying the gain thereof in accordance with the amplitude of the control signal. That is, the control tone places a negative bias on the variable gain amplifier 26, thus reducing its gain and correspondingly the level of the music and/or sound effects being transmitted by this amplifier. Various types of variable gain systems may be used, such as disclosed and claimed in Singer Patent No. 2,274,505, of February 24, 1942.

As mentioned above, in addition to having the control tone begin reducing the level of the currents corresponding to the background sounds prior to the beginning and to begin increasing the level prior to the end of each dialogue sequence, the values of the timing elements 33-34 are so chosen in conjunction with the condenser in the grid circuit of the variable gain amplifier 75 that it requires 15 frames to fade the background

sounds to any desired predetermined level and 29 frames to fade these sounds back in again. These times correspond to slightly over $\frac{1}{2}$ second and 1 second, respectively, and aid in securing the smooth transition between background and dialogue for high quality recording.

Thus, by placement of the control track sections with respect to the dialogue sequences, the reduction of the background effects level is begun 10 frames before the beginning of the dialogue to insure understanding the first word of the dialogue, the reduction in level continuing into 5 frames of the dialogue to insure understanding of particularly low level passages in any of the dialogue sequences. By extending the rate of reduction over a period of more than $\frac{1}{2}$ second, there is no distortion introduced in the form of "plops" or "amplitude bumps." By starting the increase in the background sound level 4 frames before the end of each dialogue sequence and timing this action to occur slightly over a period of 1 second duration, there will be no undesirable silence immediately after the dialogue to cause a listener to be aware that the background signal level has been reduced during the dialogue sequences.

For the above timing values, the condenser 63 had a value of 0.25 mfd. and the resistor was 250,000 ohms, the transformer 60 was an RCA RT-525, and the rectifier 62 was an RCA 6HG. The value of the condenser in grid circuit of the variable gain amplifier was 0.25 mfd. Although the above timing and the 10 and 4 frame anticipatory starting has been found preferable in this particular embodiment of the invention, it is to be understood that other values may be used since, it is only necessary to vary the length of the control tone sections with respect to the length of the dialogue sequences and vary the timing filter constants to provide the action desired.

From the above, it will be noted that the background sounds will be maintained at a predetermined low safe level as long as the control tone is present, and there will thus be no rise in the music and/or sound effects level during pauses between words or sentences, regardless of the length of the pauses. Furthermore, the mixer is able to control the amount of reduction of the background during the rerecording operation by a simple adjustment of a potentiometer on his console which varies the amplitude of the control tone as impressed on the tone rectifier and which remains constant thereafter. The amount of anticipation is obtained by the manner of intercutting the control track constant amplitude-constant frequency control tone sections, while the rate of rise and fall of the background signal is determined by the values of the timing filter elements. With such a control track system, several reels of control track may be recorded and sections cut therefrom in the lengths required and after use on a particular picture, the sections may be returned to their reels and subsequently recut or spliced to construct control tracks for other sound tracks for subsequent pictures, there thus being no film waste.

I claim as my invention:

1. A rerecording system comprising a plurality of sound reproducers for reproducing a respective plurality of sound tracks, means for amplifying currents generated by said sound tracks, means for manually varying the amplitudes of said currents, a reproducer for reproducing a control track, means for utilizing the currents generated by said control track reproducer for varying the amplitude of the currents generated by at least

one of said sound tracks, and means for manually varying the output from said reproducer of said control track.

2. A rerecording system in accordance with claim 1 in which said control track is a track of constant frequency and constant amplitude.

3. A rerecording system adapted to combine a dialogue track with a background effects track, said system comprising a reproducer of said dialogue track, a reproducer of said background effects track, a reproducer of a control track, means for manually controlling the volume of the currents from each of said reproducers, means for combining the currents from said dialogue reproducer and from said background effects reproducer, and means for utilizing the output of said control track reproducer for automatically varying the amplitude of said background effects track with respect to said dialogue track before the combination thereof.

4. A rerecording system in accordance with claim 3 in which said last mentioned means includes a variable gain amplifier for said background effects currents and a rectifier-filter combination for said control track currents, said rectified currents being impressed on said variable gain amplifier for controlling the gain thereof.

5. The method of automatically controlling the mixing of a plurality of signal tracks by a control track comprising separately translating each of said plurality of signal tracks into respective corresponding electrical currents, simultaneously translating a constant amplitude control track into corresponding electrical currents, and utilizing said control track currents to vary the amplitude of at least one of said plurality of signal currents during the translation of said signal currents.

6. The method of automatically controlling the mixing of a dialogue track and a background effects track by a control track comprising separately translating said dialogue track and said background effects track into respective corresponding electrical currents, simultaneously translating a constant amplitude control track into corresponding electrical currents, and utilizing said control track currents to vary the amplitude of the background effects currents during the translating of the dialogue sequences.

7. The method in accordance with claim 6 in which said control track becomes effective to reduce the amplitude of said background effects currents substantially 10 frames in advance of the translation of said dialogue track into electrical currents and becomes ineffective substantially 4 frames before the end of the translation of said dialogue track into electrical currents.

8. The method in accordance with claim 6 in which said control track reduces the amplitude of the background effects track from maximum to minimum in approximately one-half second, and increases the amplitude of said background effects track from minimum to maximum in approximately one second.

9. The method of anticipating and timing the reduction and increase in amplitude of one signal track with respect to another signal track being combined as a single signal, comprising translating a constant amplitude control track into corresponding electrical currents, utilizing said control track currents to begin the reduction of the amplitude of one signal track approximately $10\frac{1}{4}$ of a second in advance of the beginning of a sound sequence on said other signal track, and electrically continuing to reduce the amplitude of

said one signal track approximately $\frac{5}{24}$ of a second after the beginning of said sound sequence on said other signal track.

10. The method in accordance with claim 11 in which said control track currents begin an increase in the amplitude of said one signal track approximately $\frac{5}{24}$ of a second in advance of the end of said sound sequence on said other signal track, and electrically continuing said increase in amplitude approximately one second after the end of said sound sequence on said other signal track.

11. An automatic rerecording system comprising a reproducer for a first signal track, a reproducer for a second signal track, a reproducer for a control track, the signals on said signal tracks being adapted to be mixed into a single signal, and the signal on said control track being adapt-

ed to control said mixing, means for utilizing said control track signal for varying the level of said first signal track, said control track being reproduced prior to the reproduction of said second signal track for beginning the reduction in level of said first signal track in advance of the reproduction of said second signal track, the reproduction of said control track being discontinued prior to the end of said second signal track for beginning the increase in level of said first signal track in advance of the end of the reproduction of said second signal track, and means included in said last mentioned means for controlling the rate of reduction and increase in level of said first signal track, said reduction from maximum to minimum being at a faster rate than said increase from minimum to maximum.
